J. N. Pierce

Inventor,

UNITED STATES PATENT OFFICE.

THOMAS J. AURAND, OF WATSEKA, ILLINOIS.

SCISSORS OR SHEARS.

SPECIFICATION forming part of Letters Patent No. 688,280, dated December 10, 1901.

Application filed January 24, 1901. Serial No. 44,572. (No model.)

To all whom it may concern:

Be it known that I, THOMAS J. AURAND, a citizen of the United States, and a resident of Watseka, in the county of Iroquois and State 5 of Illinois, have invented certain new and useful Improvements in Scissors or Shears, of which the following is a specification.

My invention is an improvement on those scissors or shears which are constructed for 10 shear-cutting, and particularly on those scissors or shears whose blades are provided with a ball-bearing.

My improvement consists in novel features of construction, as hereinafter described and 15 claimed.

In order that my invention may be fully understood, I will proceed to describe it with reference to the accompanying drawings, in which—

20 Figure 1 is a side elevation of the link with its securing means. Fig. 2 is an inside view of the blades separated. Fig. 3 is a plan view of my improved scissors or shears. Fig. 4 is a transverse section taken on the line 4-4 of 25 Fig. 3.

1 is an inner blade formed with a thumb-opening 2, with an enlargement 3 at one edge having a pivot-opening 4, with an ear 5 at the opposite edge having a pivot-opening 6 30 and a segmental ball-groove 7 on its inner face concentric with the pivot-opening of the enlargement.

35 8 is an outer blade formed with a finger-opening 9, with an enlargement 10 at one edge, having a pivot-opening 11, with a segmental recess 12 at the opposite edge concentric with the pivot-opening of its enlargement, with a segmental ball-groove 13 on its inner face, registering with the ball-groove 7 of the inner 40 blade, and a segmental depression 14 in the outer face, leaving a flat narrow bead 15 at the edge of the segmental recess and a flat boss 16 at its enlargement.

45 17 designates antifriction-balls adapted to run freely in the segmental ball-grooves.

Extending across the blades and bridging the depression 14 is a link 18, formed with a pivot-opening 19 at one end, registering with the pivot-openings of the enlargements and 50 with a pivot-boxing 20 fitting in the segmen-

tal recess at the other end and having a pivot-opening 21 registering with the pivot-opening in the ear of the inner blade.

22 is a pivot screw or pin connecting one end of the link and the enlargements together 55 and secured by means of a nut 23.

24 is a pivot screw or pin connecting the other end of the link by its boxing to the ear of the inner blade and secured by means of a nut 25. 60

Having thus described my invention, the following is what I claim as new therein and desire to secure by Letters Patent:

1. Scissors or shears comprising an inner blade formed with an enlargement at one edge 65 having a pivot-opening, with an ear at the opposite edge having a pivot-opening, with a segmental ball-groove on its inner face concentric with the pivot-opening of the enlargement, an outer blade formed with an enlargement at one edge having a pivot-opening with a segmental recess at the opposite edge concentric with the pivot-opening of its enlargement, and with a segmental ball-groove on its inner face registering with the 70 ball-groove of the inner blade, antifriction-balls located in the ball-grooves, a link extending across the blades, formed at one end with a pivot-opening registering with the pivot-openings in the enlargements, and with 80 a boxing at the other end fitting in the segmental recess and having a pivot-opening registering with the pivot-opening in the ear, and pivots whereby the link is connected to the blades. 85

2. Scissors or shears comprising an inner blade formed with an enlargement at one edge having a pivot-opening, with an ear at the opposite edge having a pivot-opening, with a segmental ball-groove on its inner face 90 concentric with the pivot-opening of the enlargement, an outer blade formed with an enlargement at one edge having a pivot-opening, with a segmental recess at its opposite edge concentric with the pivot-opening of its 95 enlargement with a segmental ball-groove on its inner face registering with the ball-groove on the inner blade, and with a segmental depression in its outer face leaving a flat narrow bead at the edge of the segmental recess 100.

and a flat boss at its enlargement, antifriction-balls located in the ball-grooves, a link extending across the blades, formed with a pivot-opening at one end registering with the 5 pivot-openings of the enlargements and with a pivot-boxing at the other end fitting in the segmental recess and having a pivot-opening registering with the pivot-opening in the ear

and pivots whereby the link is connected to the blades.

In testimony whereof I have affixed my signature in the presence of two witnesses.

THOS. J. AURAND.
